UNITED STATES PATENT OFFICE.

NICHOLES FRANCIS MURPHY, OF BAKERSFIELD, CALIFORNIA.

SPIKE-PULLER.

SPECIFICATION forming part of Letters Patent No. 703,443, dated July 1, 1902.

Application filed January 6, 1902. Serial No. 88,694. (No model.)

To all whom it may concern:

Be it known that I, NICHOLES FRANCIS MURPHY, a citizen of the United States, residing at Bakersfield, in the county of Kern and State of California, have invented a new and useful Spike-Puller, of which the following is a specification.

The object of this invention is to provide a simple and powerful spike-puller of few parts 10 by means of which the laborer will be enabled to pull the spikes with great ease, convenience, and rapidity.

Another object of this invention is to provide a spike-puller the jaws of which can be 15 cheaply made of cast-steel and can readily be replaced by the workman on the ground without the necessity of taking the tool to a blacksmith-shop.

Another object of this invention is to provide 20 a spike-puller which can be readily adapted for pulling either large or small spikes and which will also pull headless spikes.

The accompanying drawings illustrate my 25 invention.

Figure 1 is a perspective view showing the tool in position for pulling the spike. Fig. 2 is a section of the same cutting through the pivot. Dotted lines indicate the position of 30 parts when the tool is open to receive the spike. Solid lines show the position of the parts after the spike has been gripped. The spike is shown partly drawn. Fig. 3 is a side elevation of the spike-puller in use. Fig. 4 is a section of the block on the line of the 35 pivot.

1 indicates a forked lever having a heel or fulcrum 2 to rest upon the top of the railway rail 3.

40 4 indicates a key-block pivoted between the forks by a pivot-bolt 5, which extends through the forks $\alpha\alpha'$ of the lever and is held in place by suitable means, such as the key 6.

7 7' indicate two slotted curved clamping- 45 jaws pivoted between the forks on opposite sides of the key-block 4, with their concaved faces 8 presented toward the block to engage the same.

9 9' indicate the gripping edges of the jaws. 50 10 10' indicate the slots in the jaws, respectively, through which the pivot-bolt is passed.

The key-block is grooved, as at 11 11', at the sides to form slideways in which the jaws play, respectively.

55

12 indicates a seat or socket in the under side of the block to receive the head of the spike to assist in centering the tool to bring the jaws in proper position on opposite sides of the spike. The block is hollow, as at 13 60 14, in order to lighten the block. The upper hole 14 provides a handle by which the block can be handled. The fulcrum-heel 2 of the lever 1 is preferably rounded on its upper rear face, as at 15, and the front lower face 65 16 is plain and flat, thus forming a sharp edge 17 to rest upon the rail 3 to prevent slipping.

In practical operation the laborer will drop the tool down onto the head of the spike, 70 taking care to allow the head of the spike to come between the jaws and into the socket 12, the jaws being thrown upward, as indicated in dotted lines in Fig. 2, and spread apart at the bottom to allow the spike to come 75 between them. The fulcrum-heel will then be rested on the rail and the lever pressed down, thus drawing the key-block up between the rounded faces of the jaws, thus throwing the upper ends of the jaws apart 80 and the edges toward each other to grip the spike. The curvature of the jaws gives considerable latitude of movement for adjusting the tool for different-size spikes. An extra set of jaws with greater or less curvature than 85 that shown may be provided for pulling larger or smaller size spikes.

The key-block and jaws are so constructed that the jaws practically slide between the key-block and parts of the lever, and as the 90 key-block moves away from the gripping portions 9 and 9' of the jaws said portions are forced together by the action of the key-block on the body of the jaws.

What I claim, and desire to secure by Letters Patent of the United States, is—

1. A spike-puller comprising a forked lever; a key-block pivoted between the forks; and two slotted curved clamping-jaws pivoted between the forks on the opposite sides of the block with their concave faces in contact with the block; the pivot extending through the slots and key-block.

2. A spike-puller comprising a lever; a key-

block carried by the lever; and two clamp-jaws constructed to slide between the block and parts of the lever; said block being constructed to force the gripping portions of the jaws toward each other as the block moves therefrom.

In testimony whereof I have signed my

name to this specification, in the presence of two subscribing witnesses, at Bakersfield, California, this 27th day of December, 1901. ¹⁰

NICHOLAS FRANCIS MURPHY.
